PIVOTED JAW, SLOTTED HEAD TOOL FOR SPEEDOMETER CABLES AND THE LIKE

Vern G. Beaman, Englewood, and Ralph C. Surratt, Denver, Colo.

Application September 12, 1952, Serial No. 309,316

8 Claims. (Cl. 81—53)

This invention relates to tools and more particularly to tools for turning a speedometer cable collar or the like. Threaded connections are sometimes found in relatively inaccessible places or confined spaces. Thus, the collar by which a speedometer cable is attached to a drive shaft or similar connection, is often disposed in a position at which access thereto by a pipe wrench or pair of pliers is difficult, if not impossible. Quite often, a speedometer cable collar is located between two parts, such as between a brake housing and a transmission housing, and the space is insufficient to permit the insertion of the usual type of wrench for a "hex" head, and the cable itself prevents the use of a "hex" socket wrench. Thus, such collars are conventionally made round and knurled about the periphery so that a mechanic by using his fingers, can turn the collar, in the event that the pressure required is no more than that which can be exerted by the fingers. However, after a long period of use, it is often difficult, if not impossible, to loosen the collar by the fingers. Also, merely tightening by use of the fingers does not always insure a sufficiently tight connection that the collar will not come loose during use. Thus, it is sometimes necessary to loosen the collar with a chisel inserted into the space and engaging a point on the periphery of the collar while the chisel is held substantially tangential to the collar, and then striking the other end of the chisel with a hammer. The collar may also be tightened in this manner, but such operations with a chisel are generally slow and time consuming, and also tend to damage the collar. In addition to speedometer cable collars, there are other connections with respect to which the confined space in which such a connection is located, as well as a part associated therewith and extending therefrom, prevents the use of the more usual tools for loosening or tightening the connection.

Among the object of this invention are to provide a tool for turning a connecting part disposed in a relatively inaccessible position, such as a speedometer cable collar; to provide such a tool which is adapted to turn a connecting part from which extends an associated part which prevents the use of a conventional tool, such as a socket wrench; to provide such a tool which may be actuated to turn a speedometer cable collar or the like in either direction, so as to tighten or to loosen the same; to provide such a tool which tends to clamp the part to be turned more tightly as the tool itself is turned in the direction in which the part is to be turned; to provide such a tool which is comparatively simple in construction yet may be made in more than one embodiment; to provide such a tool which may be manufactured with comparative ease; and to provide such a tool which is sufficiently rugged to withstand the rigors of hard usage.

Additional objects and the novel features of this invention will become apparent from the description which follows, taken in connection with the accompanying drawings, in which:

Fig. 1 is a fragmentary side elevation of a speedometer cable collar and adjacent parts, with dotted lines indicat-

ing the position of a tool constructed in accordance with this invention for loosening or tightening the collar;

Fig. 2 is a side elevation of a tool constructed in accordance with this invention, in operative position on a speedometer cable collar;

Fig. 3 is a longitudinal section of the tool of Fig. 2;

Fig. 4 is a transverse section taken along line 4—4 of Fig. 2;

Fig. 5 is an end view of the tool of Fig. 2, taken from the position of line 5—5 of Fig. 3;

Fig. 6 is a transverse section taken through the handle of the tool, along line 6—6 of Fig. 3;

Fig. 7 is a side elevation of a tool forming an alternative embodiment of this invention;

Fig. 8 is an end view of the tool of Fig. 7, taken from the handle end at the position of line 8—8 of Fig. 7;

Fig. 9 is a longitudinal section of the tool of Fig. 7, taken along line 9—9 of Fig. 8;

Fig. 10 is a transverse section taken along line 10—10 of Fig. 7; and

Fig. 11 is an end view of the tool, taken from the head end at the position of line 11—11 of Fig. 7.

As illustrated in Fig. 1, a sheathed speedometer cable 10 may be connected by an annular collar 11 to a threaded connection 12 mounted on a housing 13, into which the speedometer cable extends for engagement with a suitable interlocking device (not shown) by which the rotation of a drive shaft or the like may be transmitted through the speedometer cable to an instrument such as a speedometer, for indicating the speed of the drive shaft or the speed of a vehicle driven through the drive shaft. The connection 12 may be disposed in a relatively inaccessible position, such as between a transmission housing 14 and a drive shaft brake housing 15. As will be evident, due to the limited space in which the collar 11 is disposed, it is difficult if not impossible to tighten or loosen the collar by means of a usual open end wrench, while the cable 10 itself prevents the use of a socket wrench. Thus, if the collar 11 were hexagonal in shape, no advantage would be obtained thereby. While the collar 11 is knurled, as shown, not only is the space between the housings 14 and 15 limited, so that access thereto by the fingers is comparatively difficult, but the collar 11 many times cannot be loosened by the fingers, and also adequate tightening by the fingers is difficult.

A tool constructed in accordance with this invention may comprise a handle 18 and a head H, in use the handle 18 lying alongside the cable 10, as shown in Fig. 2, and also indicated in dotted lines in Fig. 1, while the head H is adapted to encircle the collar 11, so that the tool may be turned about the axis of cable 10, in one direction while tightening the collar and in the opposite direction while loosening the same. The tool also includes a jaw 19 which is associated with the head H and which is pivoted about a longitudinal axis, i. e. preferably the axis of the handle 18. The jaw 19 is preferably a dual jaw having a wing 20 on one side and a wing 21 on the opposite side, each wing 20 and 21 being generally an arcuate segment in form and adapted to engage the collar 11, so as to be wedged against the collar and also force the collar 11 against the inside of the head H on the opposite side of the latter, as in the manner illustrated in Fig. 4. Preferably, wing 20 of the jaw 19, which extends from its axis in the direction in which the collar 11 is to be turned for loosening the collar, i. e. the direction of the arrow 22 of Fig. 4, engages the collar 11, while the opposite wing 21 of the jaw 19 engages the collar when the collar is to be turned in the opposite direction, i. e. for tightening.

As in Fig. 3, the head H is preferably generally cup-shaped, having an annular side wall 23 and a generally flat bottom 24 and may be integral with the handle 18

and disposed in a position such that its longitudinal axis is parallel to but spaced laterally from the longitudinal axis of the handle 18. The inside of the head sidewall 23 is preferably circular, and is provided with a longitudinal slot 25, extending through the sidewall 23 at a point opposite the handle 18, while an extension 26 of slot 25 extends laterally through the bottom 24 of the head and may be slightly enlarged at the center, as in Figs. 5 and 6. The outer periphery of the head may be generally circular, except adjacent the handle 18, at which the head may be provided with a laterally extending portion 27 having two sides 28, as in Fig. 5 which extend tangentially from the circle of the remainder of the outer periphery, to meet in an arc at a point laterally beyond the axis of the handle 18. As will be evident, the longitudinal slot 25 and its extension 26 permit the head H to be passed over the speedometer cable 10, and the head moved to the positions of Figs. 1 and 2, in which the head H encircles the collar 11 and the cable 10 passes through the central portion of the extension slot 26 in the bottom of the head.

The head 18 is also provided with a transverse slot 29 which extends through the laterally extending portion 27 of the head H and also into the sidewall 23 of the head for a sufficient distance at each side so that the jaw 19 may be rotated within the slot 29. In the embodiment of Figs. 2-6, the handle 18 is provided with a central longitudinal bore, which also extends through the head H and through which a pin or shaft 30 extends, jaw 19 being mounted on shaft 30. A suitable hole may be drilled through the jaw 19 and the shaft 30, so that a locking pin 32 may be inserted therein, to secure the jaw 19 to the shaft 30. The opposite end of the shaft 30 is provided with a knob 31, which may be attached to the shaft 30 or made integral therewith, the knob 31 preferably being knurled so as to be more readily grasped by the user to turn the jaw 19. To provide an engagement between the tool and the collar 11 which is less likely to slip, the inside of the sidewall of the head, or the jaw wings, or both, may be provided with longitudinally extending serrations. Thus, as in Figs. 3 and 4, the inner edge of each of the wings 20 and 21 may be provided with serrations 33.

As will be evident, the head H may be inserted over the speedometer cable 10 and moved therealong until it encircles the collar 11, with the jaw 19 in the position of Fig. 5, the jaw being suitably held in position by means of the knob 31. Then, depending upon whether the collar 11 is to be loosened or tightened, the knob 31 is turned so as to move the wing 20 or 21 of the jaw 19 into engagement with the collar 11. Turning pressure on knob 31 is preferably continued during loosening or tightening of the collar 11, while the tool is rotated around the cable 10. As will be evident, only a small clearance alongside collar 11 is necessary for rotation of the tool about the axis of the collar 11.

The embodiment of the tool of this invention illustrated in Figs. 7-11 is operated similarly to the embodiment illustrated in Figs. 2-6, but the handle 18' and the head H' of the former are made separately, thus eliminating the separate shaft 30 and also reducing the material necessary to be machined in order to form the head and handle as an integral part, as in the embodiment of Figs. 2-6. Thus, the head H', similarly to the head H, Figs. 2-6, has a generally annular sidewall 23' provided with a longitudinal slot 25' opposite the handle 18' and a flat bottom 24' into which slot 26' extends, the slot 26' being larger at the center, if desired, than the slot 26 of the head H. In addition, the outer periphery of the head H' is circular, except for the laterally extending portion 27' which is provided with tangential sides 28' meeting in an arc laterally of the axis of the jaw 19'. The jaw 19' is again preferably a dual jaw having wings 20' and 21' which are adapted to be turned into engagement with the collar 11 of Figs. 1 and 2, the jaw again moving within a transverse slot 29'. Instead of a separate shaft for ro-

tation of the jaw 19', the handle 18' may be provided with an extension or pin which extends through the head H' and the jaw 19' and which includes a cylindrical section 35 journaled in the head H', as in Fig. 19. A second cylindrical section 36 is smaller, because of the reduced thickness of the head, while a square or non-circular section 37 extends through the jaw 19' and cooperates with a similarly formed slot in the jaw to attach the same thereto for rotation, and a third and still smaller cylindrical section 38 extends through a similar bore in the portion of the head beyond the slot 29'. The bore for the cylindrical section 38 may be then counterbored slightly at the end, so that the end of the pin may be peened to retain the handle in the head, although a relatively snug fit, such as a drive fit, between the non-circular section 37 and the slot therefore in jaw 19', may be utilized for this purpose.

The exterior of handle 18' is preferably knurled, to provide a better grip thereon, so that the handle 18' may be turned to force the wing 20' or 21' of jaw 19', as the case may be, into engagement with the collar to be loosened or tightened. As indicated, the head sidewall or the wings, or both may be provided with serrations on the inside to provide a better grip on the collar 11. Thus, as in Figs. 9-11, the inside of the head sidewall 23' may be provided with serrations 40, extending between the longitudinal slot 25' into transverse slot 29', while one or both of the wings 20' and 21' of the jaw 19' may be provided with a small number of serrations adjacent its outer end, on the inside, such as serrations 41 on the inside of the collar loosening jaw wing 20'.

From the foregoing, it will be evident that the tool of this invention fulfills to a marked degree the requirements and objects hereinbefore set forth. The use of a head adapted to encircle the part to be loosened or tightened, in conjunction with a jaw which is movable about a longitudinal axis, insures that the part to be loosened or tightened will be forced into engagement with the head and an effective grip will be maintained thereon. The longitudinal slot in the head permits the tool to be passed over a part which extends axially from the part to be loosened or tightened, while the transverse slot in the head permits the jaw to be placed so that a minimum of clearance on the outside of the part being loosened or tightened is necessary. The use of the handle or means such as a shaft associated with the handle, to turn the jaw, not only simplifies the construction but also reduces the clearance space necessary for operation of the tool. This feature also simplifies the operation of the tool, enabling it to be operated by use of only one hand and permits the entire tool to be rotated while loosening or tightening the desired part. The use of a dual jaw, which may be turned in one direction to engage a part to be loosened, or in the opposite direction to engage a part to be tightened, provides a desirable flexibility of operation. Since the jaw is preferably turned in the direction in which the desired rotation of the part to be loosened or tightened is to be imparted, pressure of the jaw is readily continued during rotation of the part. As will be evident, the small number of parts in the two embodiments of the invention illustrated and described, enables the tool to be manufactured with comparative ease, while the parts may be made sufficiently heavy so that ruggedness is readily obtained.

Although two embodiments have been illustrated and described, it will be understood that other embodiments may exist, and various changes made therein, all without departing from the spirit and scope of this invention.

What is claimed is:

1. A tool for turning a speedometer cable collar and the like, comprising a handle; a generally cup-shaped head at the forward end of said handle with its axis extending longitudinally and spaced laterally from the axis of said handle, said head having a longitudinal slot extending through one side thereof opposite said handle and into

the rear end thereof, said slot being of a size to permit passage of said cable to a central position with respect to said head, and said head also having a transverse slot in the side thereof adjacent said handle and extending away from said handle axis in each direction; a dual jaw pivoted on a longitudinal axis within said transverse slot, said jaw being generally arcuate in shape and having an inner edge corresponding in shape to the inside of said head along said transverse slot, said jaw extending a comparatively substantial distance along said slot in each direction from its axis; a pin extending from said handle through said head as a pivot for said jaw; and means at least associated with said handle for turning said pin to cause said jaw to pivot.

2. A tool for turning a speedometer cable collar and the like, as defined in claim 1, wherein said pin is integral with said handle, and said handle is formed as a part separate from said head.

3. A tool for turning a speedometer cable collar and the like, as defined in claim 1, wherein said head is integral with said handle, and said pin extends longitudinally within said handle and is provided with a knob at the rear end thereof for turning said pin.

4. A tool for turning a speedometer cable collar and the like, as defined in claim 1, wherein the inner edge of said housing, between said longitudinal slot and said lateral slot, is provided with longitudinal serrations.

5. A tool for turning a speedometer cable collar and the like, as defined in claim 1, wherein the inner edge of said head is circular, and the outer edge of said head is circular with a portion thereof having sides extending tangentially at each side of and meeting arcuately at a point disposed laterally from said pivot axis on the side of said pivot axis opposite said longitudinal slot.

6. A tool for turning a speedometer cable collar and the like, comprising a handle; a generally cup-shaped head at the forward end of said handle with its axis extending longitudinally and spaced laterally from the axis of said handle, said head having a longitudinal slot extending completely through one side thereof opposite said handle and past the center thereof toward said handle, said slot being of a size to permit lateral passage of said cable to a central position with respect to said head; a jaw pivoted on a longitudinal axis and associated with said head so as to engage said collar when turned; and means at least associated with said handle for turning said jaw.

7. A tool for turning a speedometer cable collar and the like, comprising a handle; a generally cup-shaped head at the forward end of and integral with said handle, the axis of said head extending longitudinally and being spaced laterally from the axis of said handle, said head having a flat bottom and a generally annular sidewall with a longitudinal slot extending through said sidewall opposite said handle and into said bottom, said slot being enlarged centrally of said bottom and being adapted to permit passage of said cable to a central position with respect to said head, and said head also having a trans-

verse slot in the side thereof adjacent said handle and extending away from said handle axis in each direction; a dual jaw pivoted on a longitudinal axis within said transverse slot, said jaw having a generally arcuate wing extending to each side and having an inner edge corresponding in shape to the inside of said head along said transverse slot, said jaw extending a comparatively substantial distance along said slot in each direction from its axis and the inner edge of each wing being provided with longitudinally extending serrations; a pin extending through said handle and said head as a pivot for said jaw; and a knob on said pin at the opposite end of said handle for turning said pin to cause said jaw to pivot.

8. A tool for turning a speedometer cable collar and the like, comprising a handle; a separate, generally cup-shaped head mounted at the forward end of said handle with its axis extending longitudinally and spaced laterally from the axis of said handle, said head having a flat bottom and a generally annular side wall with a longitudinal slot extending through said sidewall opposite said handle and into said bottom, said slot being enlarged centrally of said bottom and being adapted to permit passage of said cable to a central position with respect to said head, said head also having a transverse slot in the side thereof adjacent said handle and extending away from said handle axis in each direction, and the inner edge of said sidewall being provided with longitudinal serrations between said longitudinal slot and said transverse slot; a dual jaw pivoted on a longitudinal axis within said transverse slot, said jaw having a generally arcuate wing extending to each side and having an inner edge corresponding in shape to the inside of said head along said transverse slot, said jaw extending a comparatively substantial distance along said slot in each direction from its axis; and a pin integral with said handle and extending from said handle through said head as a pivot for said jaw, said pin having a first cylindrical section journaled in said head, a second cylindrical section of lesser diameter journaled in said head, a non-circular section within said jaw, and a third cylindrical section of still lesser diameter and journaled in said head beyond said transverse slot, said head having a bore provided with sections of a diameter corresponding to said first, second and third cylindrical sections and said jaw having a slot corresponding in shape to and engaging said non-circular section.
